To all whom it may concern:

Be it known that I, STANLEY A. COHEN, a citizen of the United States, and a resident of the city of New York, borough of Manhattan, 5 in the county and State of New York, have invented and produced a new, original, and ornamental Design for a Poker-Chip, of which the following is a full, clear, and exact description.

10 Reference is to be had to the accompanying drawing, in which the figure is a face view of a poker-chip, showing the design.

The design consists of the representation of a shield bearing on its face the representation 15 of a raging lion in horizontal position

Having thus described my invention, I claim as new and desire to secure by Letters 20 Patent—
